BENDING AND BEVELING MACHINE

Richard Seifried, Inglewood, Calif., assignor to
 North American Aviation, Inc., Inglewood,
 Calif., a corporation of Delaware

Application October 26, 1942, Serial No. 463,327

7 Claims. (Cl. 153—32)

My invention relates to a bending and beveling machine of the general character shown in my pending application Serial No. 437,947, filed April 7, 1942.

The principal object of the present invention is to provide means for automatically maintaining a constant tension on material during the bending and beveling operation.

Still another object of the invention is to provide means for automatically maintaining constant tension at opposite ends of the strip or other material even though the shape in which it is being bent is asymmetrical.

A further object of the invention is to provide such a machine that will eliminate the necessity of providing different tracks for bending different shapes.

Another object is to provide means in such a machine that will minimize tearing effect upon and nicking of the material.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a plan view of an embodiment of my invention.

Fig. 1a is a similar view of a suggested pressure fluid pump and its motor.

Fig. 2 is a front elevation of the embodiment shown in Fig. 1.

Fig. 3 is an enlarged section taken on the line 3—3 of Fig. 2.

Fig. 4 is an enlarged, broken plan view looking in the direction of arrows 4—4 of Fig. 2.

Fig. 5 is an enlarged section taken on line 5—5 of Fig. 1.

Fig. 6 is an enlarged section taken on line 6—6 of Fig. 1.

Fig. 7 is a diagrammatic view of a pressure system used in the present embodiment.

Referring more in detail to the drawings, the reference numeral 8 generally designates frame work for the present machine. A platform 9

is mounted upon the frame 8 and is in turn employed to support a die block or mandrel 10. The die block 10 may have a groove 12 therein and the die face 13 thereof may be vertical, or inclined if the material is to be beveled, as shown in my said co-pending application.

A flange 14 on the material to be formed fits in the groove 12 while the body 15 of the material conforms with the face 13 of the die block. Adjusting screws 16, mounted in a bracket 17 on the frame, adjustably support the die block 10 at the rear thereof. Interlocking, sliding members 18, or other suitable means, may be employed for supporting the die block 10 upon the platform 9. The frame 8 includes curved channel members 19, the channels of which face outwardly and preferably provide journals for sheaves 20. Other sheaves 21 are supported at opposite sides of a beam 22 extending rearwardly on the frame of the machine, by means of a cross support 23.

Idlers 24 are arranged at the rear of the frame-work of the machine. Pulleys 25 are provided at the foot, at the front center of the machine. Pulleys 26 are disposed at the bottom front corners of the frame 8, while pulleys 27 are provided at the sides of the front of the machine.

Supporting arms 28 and 29 are pivoted on the frame of the machine at 30 and 31 respectively. Cylinders 32 and 33 are pivotally mounted upon the arms 28 and 29 respectively. It is believed clear without further illustration that piston rods 34 and 35 respectively carry pistons within the cylinders 32 and 33. Means 36 are indicated for pivotally mounting the cylinders upon the pivoted arms 28 and 29. The pivots for the cylinders 32 and 33 are shown at 37 and 38 respectively.

Vise-like members 39 provided with set screws 40 are arranged to grip ends of the material 15. Heads 41 on the piston rods 34 and 35 have lateral slideable connections with the vise-like members 39. Additional pivotal journals 43 are provided for the pivots 30 and 31 of the arms 28 and 29.

Conduits 44 and 45 connect with opposite ends of the cylinder 32, while conduits 46 and 47 connect with opposite ends of cylinder 33. The conduits 44 and 45 are joined in a double conduit 48 while the conduits 46 and 47 are joined in a double conduit 49.

Referring especially to Fig. 7, a four-way valve 50 of any suitable and well known construction, may be employed to control the pres-

sure fluid from a branch 51 of the pressure line 52 to one end or the other of cylinder 32. A handle 53 is arranged to control the valve 50. A second four-way valve 54 is arranged to connect another branch 55 of the pressure line 52 with one end or the other of the cylinder 33. A handle 56 controls the valve 54. The ends of the cylinders that are not connected with the pressure line 52 are connected with a return pipe 57 which in turn connects with a conduit 58 that leads back to the intake side of a pump 58. The pressure line 52 is connected with the pressure side of the pump 58. Excess fluid from the return pipe 57 discharges into a reservoir 60, from which it may be drawn by the pump, as desired. A motor 61 actuates the pump. In practice, the reservoir 60, pump 58 and motor 61, may be suitably mounted as a unit such as shown in Fig. 1a, on any convenient supporting surface adjacent to the rear portion of the machine, and, for example, in approximately the relation thereto existing between Figs. 1 and 1a, although this relation may be varied within a considerable range in use, depending upon available space.

An automatic relief valve 62 is connected between the pressure line 52 and the exhaust line 57 by means of pipes 63 and 64 respectively. Thus excess pressure in the line 52 by-passes back into line 57, when the pressure in the line 52 reaches a predetermined point. A plate 66 provides a cover for the valves 50 and 54, at the front of the machine.

A still further relief means is provided by a conduit 67 which leads from the exhaust line 56 to a manual relief valve 68, which is controlled by handle 68a, also arranged behind the plate 66. The manual relief valve 68 is in turn connected with the automatic relief valve 62 by a line 69. Pressure in line 69 may exhaust through the automatic relief valve 62 to the return pipe 57 by means of a conduit 70.

On the under side of each of the pivoted arms 28 and 29 is anchor means for the cables controlling that particular arm. For example, a bracket 71 supports anchor screws 72 and 73. A head member 74 is also supported on the under side of the pivoted arm by bracket means 75. End of cable 76 is fastened to the screw 72 and thereby anchored in place. End of cable 77 is fastened to the screw 73 and thereby anchored in place. The cables 76 and 77 pass each other in a groove 78 in the block 74, extending in opposite directions.

The cable 76 passes around the roller 27, then extends downward about the roller 26 and across the bottom at the front of the machine, around the roller 25 and then rearwardly to a sheave 79 and up around a drum 80 included in a winch 81.

The cable 77 extends around the roller 21, around the idler 24 and on to the drum 80. The cables 76 and 77 are wound upon the drum 80 in opposite directions, as perhaps best shown in Fig. 3. The cables 76 and 77 may be wound at opposite ends of the drum 80 or in any other desired arrangement that will not interfere with their individual winding or unwinding.

Similar anchor screws 82 are supported under the pivoted arm 28 by bracket means 83, in the same manner as shown in Fig. 4 and described in connection therewith. Cables 84 and 85 are thus anchored under the pivoted arm 28. The cable 84 extends around pulleys 27, 26 and 25, and back around sheave 86. The cable 84 then winds upon a drum 87 also included in the winch 81.

The cable 85 passes around the sheave 21 and the idler 24 and is also wound upon the drum 87. The winch 81 is driven by a reversible motor 88 through the intermediary of driving belt means 89 and reduction gear 90 of conventional and suitable form.

An automatic switch means is provided in an upstanding frame 91 at the rear of the machine. A wire 92 is passed around pulleys 93 and 94 depending within the frame 91. Blocks 95 and 96 at opposite portions of the wire 92 are respectively arranged to trip levers 97 and 98 of electric switches 99 and 100. The block 95 rides up and down on the rod 101, while the block 96 rides up and down on the rod 102. The opposite ends of the wire 92 are respectively wound around reduced portions 103 and 104 of the drums 87 and 80 respectively. The position of the block 96 in Fig. 6, in its upward motion, is just prior to tripping the lever 98. The arms 28 and 29 would be almost at their point of greatest movement toward the beam 22 in this position of the block 96. When the block 96 trips the lever 98, the motor 88 is cut off. Suitable switch means 105 is arranged at the front of the machine for manually closing the circuit of motor 88 to operate the motor in a reverse direction, whereby to swing the arms 28 and 29 away from the beam 22 and toward the front of the machine. When the arms 28 and 29 reach their predetermined forward limits, the block 95 trips the lever 97 and breaks the circuit of the motor 88. A switch button 106 may be arranged to break the circuit manually. A manual switch button 107 also at the front of the machine is connected to close the circuit of the motor 88 to operate same in the opposite direction from the operation actuated by the switch button 105. Manual button 108 is connected to break the circuit of the motor 88 when the arms 28 and 29 have swung to the desired point in a direction toward the beam 22.

It is to be understood that the automatic cut-off switches 99 and 100 or the manual cut-off switches 106 and 108 may be used alternatively.

In the operation of the machine, the die block 10 is positioned upon the platform 9. Material 15 to be bent is placed against the die block with the flange 14 of the material disposed in the groove 12 of the die block.

Ends of the material 15 are gripped in the vises 39 by means of the set screws 40. The vises 39 are then inserted into their slidble connection with the head members 41.

It is believed clear without illustration that a pressure gauge may be utilized in the line 52 in order to indicate the amount of pressure to which the pistons in cylinders 32 and 33 are subjected. The relief valve 62, which is of conventional construction, is set to permit the return

of pressure fluid to the reservoir 60 and to the intake of the pump 58, if the pressure in the line 52 rises above a predetermined point. It is preferred to have the pump provide constantly a greater pressure than said predetermined amount

and to by-pass the excess back to the intake of the pump, in order to provide the desired pressure upon the pistons at all times, during movement of the arms 28 and 29. It is also to be understood that either hydraulic or pneumatic pressure may be used, although hydraulic pressure is preferred because of the non-compressibility of the liquid.

The handles 53 and 65 are turned to positions to permit the pressure from the pressure line 52 to flow through the conduits 45 and 46, thus ex-

erating the desired tension upon the material 15. The switch 107 is thereupon actuated to close the circuit of motor 88 and thereby effect rearward swinging movements of the arms 28 and 29 and their therewith pivotally supported cylinders 32 and 33. The motor 61 and pump 58 are, of course, continually operating during the bending operation.

The tension of the ends of the material 15 is maintained constant, irrespective of the shape of the die block 10 and irrespective of whether the two halves of the die block 10 are symmetrical. The pressure system shown and described causes pressure to be balanced at opposite sides of the pistons in the cylinders 32 and 33, for if the pressure increases on the side of the piston between the piston and the material 15, then such pressure is relieved through the relief valve 62. If the pressure between the piston and the material 15 decreases below the set amount, the pump automatically builds up pressure to the desired amount, thus automatically maintaining the pressure constant against the pistons in the two cylinders, throughout the shaping of the material 15.

Due to the pivotal supports for the cylinders 32 and 33, the cylinders may swing laterally to compensate for abrupt or gradual change of shape of the die block. This pivotal means affords a straight pull upon the material, within the limits of the machine.

When the machine has reached the predetermined point of maximum travel, the switch 100 automatically breaks the circuit of the motor 88. At this point it is desirable to relieve the pressure on the material. This may be done manually by operation of the valve 68. The material 15 may then be released by unscrewing the set screws 40. The arms 28 and 29 with their supported cylinders are swung to the front of the machine by pressing the button 105, which manually closes the circuit of the motor 88, to operate the motor in the opposite direction. When the arms 28 and 29 have reached the desired forward position, the switch 99 automatically breaks the circuit by means of the block 95. The machine is then ready for the next cycle of operation.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In a machine for forming material, a frame, a mandrel platform supported horizontally on said frame, a forming mandrel adjustable forwardly and rearwardly on said platform, means for adjustably limiting rearward movement of the mandrel, pivoted arms supported and guided by the frame and swinging relative to the mandrel, material connecting means mounted on said arms, mechanism connected with the material-connecting means to draw such means away from each other during swinging movement of the arms, thereby applying tension upon the material, cable and pulley means connected to opposite sides of the arms to swing the arms in opposite directions including a winch, and means actuated by said winch for stopping operation

thereof when the arms reach the end of each swinging movement thereof.

2. In a machine for forming material, a forming mandrel, pivoted arms swinging relative to the mandrel, material connecting means mounted on said arms, mechanism connected with the material-connecting means to draw such means away from each other during swinging movement of the arms, thereby applying tension upon the material, cables fastened on the pivoted arms, a winch for winding up the cables, pulleys arranged to support the cables to move the pivoted arms toward each other by rotation of the winch in a given direction and to move the pivoted arms away from each other by rotation of the winch in the opposite direction, motor actuated means to rotate the winch in opposite directions, and winch operated means for cutting off the motor operated means at the end of each movement of the swinging arms.

3. In a machine for forming material, a supporting frame, a forming mandrel horizontally on said frame, arms having fixed pivots at their inner ends in the frame below opposite sides of the mandrel for horizontal swinging relative to the mandrel, material-connecting means to be connected with opposed portions of the material to be formed with respect to the mandrel, pressure cylinders mounted on the swinging arms for swinging movement therewith and having vertical pivotal connection with the arms for horizontal shifting movement with respect to the arms, pistons in the cylinders connected with the material-connecting means, mechanism connected to supply a substantially uniform pressure against the piston means within the cylinder means, to maintain a substantially constant pressure upon the material, and means to swing the arms around their pivots, to form the material with respect to the mandrel.

4. In a machine for forming material, a forming mandrel, arms having fixed pivots at their inner ends below opposite sides of the mandrel for swinging relative to the mandrel, material-connecting means to be connected with opposed portions of the material to be formed with respect to the mandrel, pressure cylinders pivotally mounted on the swinging arms to swing therewith and shift relative thereto, pistons in the cylinders connected with the material-connecting means, a continuously operating pressure pump having a capacity greater than that required to provide the normal pressure for the cylinders, automatic by-pass means connecting to by-pass pressure in excess of said normal pressure back to the intake of the pump, conduits connected to supply the pressure to the cylinders, flexible means connected to, and extending from opposite sides of each of the arms to swing the arms around their pivots in opposite directions with respect to the mandrel and reversible means for actuating said flexible means and simultaneously operating the arms in either direction.

5. In a machine for forming material, a forming mandrel, pivoted arms swinging relative to the mandrel, a reversible motor connected to swing the arms about their pivots, automatic switch means connected to shut off the motor when the arms have swung to their predetermined limits, manual switch means connected to actuate the motor to swing the arms to their opposite limits, automatic switch means connected to shut off the motor when the arms reach such opposite limits, both of said automatic switch means and the manual switch means op-

erating in a single cycle of operation, material-connecting means to be connected with opposed portions of the material to be formed with respect to the mandrel, pressure cylinders mounted on the swinging arms, pistons in the cylinders connected with the material-connecting means, and mechanism connected to supply a substantially uniform pressure against the pistons within the cylinders.

6. In a machine for forming material, a forming mandrel, pivoted arms swinging relative to the mandrel, a reversible motor connected to swing the arms about their pivots, switch means connected to break the circuit of the motor, a longitudinally movable connecting means, spaced switch actuating means joined by said connecting means, mechanism connected to move said connecting means longitudinally during swinging movement of the arms, the spaced actuating means being arranged to actuate the switch means to automatically break the circuit of the motor when the arms have reached their opposite predetermined limits, material-connecting means to be connected with opposed portions of the material to be formed with respect to the mandrel, pressure cylinders mounted on the swinging arms, pistons in the cylinders connected

with the material-connecting means, and mechanism connected to supply a substantially uniform pressure against the pistons within the cylinders.

- 5 7. In a machine for forming material, a forming mandrel, pivoted arms swinging relative to the mandrel, motor-driven winch means connected to swing the arms about their pivots, switch means connected to break the circuit of the
- 10 10 the winch motor, a longitudinally movable connecting means, spaced switch actuating means joined by said connecting means, means connected to be operated by the winch to move the connecting means longitudinally, the spaced actuating means being arranged to actuate the switch means to automatically break the circuit of the motor when the arms have reached their opposite predetermined limits, material-connecting means to be connected with opposed portions
- 15 20 of the material to be formed with respect to the mandrel, pressure cylinders mounted on the swinging arms, pistons in the cylinders connected with the material-connecting means, and mechanism connected to supply a substantially uniform pressure against the pistons within the cylinders.

RICHARD SEIFRIED.
